Patented May 11, 1909.

UNITED STATES PATENT OFFICE.

CHARLES P. McGREGOR, OF PITTSBURG, PENNSYLVANIA.

BLASTING DEVICE.

No. 921,144.

Specification of Letters Patent.

Patented May 11, 1909.

Application filed August 4, 1908. Serial No. 446,898.

To all whom it may concern:

Be it known that I, CHARLES P. McGREGOR, a resident of Pittsburg, in the county of Allegheny and State of Pennsylvania, have invented a new and useful Improvement in Blasting Devices, of which the following is a specification.

This invention relates to devices for use in blasting.

10 The object of the invention primarily is to prevent blow-out shots in coal mines with the disastrous consequences which frequently follow from such shots.

15 The invention is applicable in the blasting of coal, slate, mineral or other strata of earth in any or all kinds of mines, slopes, drifts, shafts, tunnels, subways, quarries or other excavations.

20 The invention will be shown and described particularly for use in the mining of coal, but it will be understood that it can be used whenever blasting is carried on for any purpose whatsoever, and all such uses are intended to be covered by the claims herein-
25 after made.

The main object of the invention is to remove the cause of the many explosions and other fatal and costly accidents in and around coal mines, due in a great measure, 30 to the dangerous and tedious methods now followed for blasting, the crude condition or construction of the blasting tools, and the dangerous conditions under which the miner is compelled to use the explosive.

35 A further object of the invention is to provide a device for blasting purposes so arranged with reference to the powder charge or cartridge in the bore hole that the charge will burn and be consumed at a uniformly 40 increasing rate throughout the entire charge to thereby generate gases in a uniformly increasing quantity and produce a uniformly accelerating force.

In the accompanying drawing, Figure 1 45 is a side view of my improved blasting device, showing the middle and outer portions broken away; Fig. 2 is a similar view showing the device with an attached cartridge; Fig. 3 is a longitudinal section through the 50 device and cartridge in the bore hole, the middle portion being broken away; Fig. 4 is an end view of the device; Fig. 5 is a cross section on the line 5—5, Fig. 3, and Fig. 6 is a perspective view showing a modified form of powder plug.

In order that the invention and its use may be fully understood, I will briefly describe the usual method of preparing and completing a blast as practiced in an up-to-date mine in the bituminous coal regions of Pennsylvania. The miner first makes a paper cartridge by wrapping the paper around his pick handle; then fills the cartridge with powder from a can; then inserts the filled cartridge into the bore hole and forces it to the rear of the hole with a tamping bar; then inserts the needle into the bore hole and forces the end thereof into the powder of the cartridge; then tamps the hole by filling the same with damp dirt or slack and forcing it back with a tamping bar until it reaches the cartridge, holding the needle with one hand while manipulating the tamping bar with the other hand, and repeating this operation until the hole is tamped to the face of the coal, after which he withdraws the needle, thus leaving a small hole or passage to the charge of powder which is ignited by means of a patent safety squib which is placed loosely in the hole or passage left by the needle.

Very frequently the blast fails to go off, which may be due to one of the following reasons: First, damp powder, second, needle not properly placed in the cartridge before tamping; third, improper tamping; fourth, improper withdrawal of the needle so that the passage for the squib to the powder charge is obstructed. In any event the process is a slow and tedious one, as well as dangerous, due to the fact that the miner in his anxiety to set off the blast so that he can begin to load the coal, frequently does not take time to do the work properly. Frequent blow-out shots also occur, and if the mine is at all gaseous, fatal explosions result therefrom.

My device is intended to greatly facilitate the preparation and completion of a blast and also do away with the danger to the miner and especially to prevent blow-out shots.

In the drawings the coal or other material to be blasted is indicated at 1; 2 indicates the bore hole in which the blast is to be inserted. The device comprises a suitable powder plug, 3, preferably conical as shown in Fig. 1, and provided at its outer end with the disk or collar, 4, which serves practically as a closure for the bore hole. This powder

plug is provided with a hole or passage, 5, therethrough for the squib, and at its outer end is provided with an internally threaded opening, 6, for receiving the reduced threaded end, 7, of the bar, 8, which likewise is provided with a squib hole or opening, 9, therethrough, communicating with the hole in the powder plug.

Surrounding the reduced inner end of the bar, 8, are gripping members comprising jaws, 10, preferably four in number as shown, which are pivotally mounted on the ring, 11, and are provided with prongs, 12, or saw teeth, 13, or both, for gripping the walls of the bore hole. These grippers are arranged to be expanded, to engage and grip the walls of the bore hole, by suitable means, that shown comprising a conical sleeve, 15, arranged to be moved inwardly inside of the grippers and expand the latter. This is accomplished by providing the bar, 8, with threads, 16, and correspondingly threading the conical sleeve, 15, internally, so that by rotating these parts relatively to each other, 25 the conical sleeve is moved inwardly to expand the grippers. The conical sleeve at its outer end is provided with sockets or holes, 17, for receiving projecting portions, 18, on the end of the tube, 19, which surrounds the bar, 8, and extends out to the face of the coal. The outer end of the bar, 8, is either square, or provided with a hole, 20, or both, so that it can be held against rotation, and the outer end of the tube, 19, is provided 35 with a hole, 21, for receiving a suitable turning tool.

The parts at their outer end are steadied by means of a plug, 22, preferably slightly wedge shaped, and which may be either 40 tubular or formed in several sections, and is inserted in the outer end of the bore hole around the tube, 19.

The powder plug, 3, preferably is conical, although it may be straight, and preferably 45 also is corrugated externally as shown at 23. Preferably also, a number of perforations, 24, are provided, communicating with the squib hole, 5, in said plug. This powder plug is inserted in the cartridge, 25, and projects into the powder, 26, contained therein. These cartridges usually are of paper, and the cartridge is secured to the powder plug by wrapping the same with twine over the corrugations as shown at 27. The end of 55 the cartridge is practically against the flange or shoulder, 4, on the powder plug. The device with a cartridge attached is forced into the bore hole until it reaches the end thereof, and the pressure on the bar inwardly causes the paper cartridge to buckle and gather, thus forming a packing or plug between the powder plug and the walls of the bore hole. After being so forced inwardly, the bar, 8, is held against rotation 60 and the tube, 19, is rotated, thus rotating

the conical sleeve, 15, and moving the same inwardly between the grippers, 10, and expanding the latter and forcing them into the walls of the bore hole. When the grippers are expanded they lie in an inclined position, as shown in Fig. 3, and hence pressure outwardly causes said grippers to dig into the walls of the bore hole, the pivotal connection of said grippers allowing them to swing out to still greater angle as they enter the coal or rock. The greater the pressure the deeper will the grippers be forced into the coal. The consequence is that when the blast is ignited these grippers prevent the device from moving outwardly and the powder plug and packing of paper described absolutely prevent a blow-out or the flame from reaching the face of the coal. In this way blow-out shots are absolutely prevented.

The inner portion, 29, of the powder plug, 3, is formed of some metal which will not produce sparks when it comes into contact with hard foreign substance. Copper is a suitable metal for this purpose. This prevents accidental ignition of the powder when the blast is being forced into the hole.

Fig. 6 shows a slightly different form of powder plug, the same being provided externally with longitudinal ribs, 30, which are practically straight from end to end. 95 The powder plug projects into the powder of the cartridge to a considerable distance, and the flame from the squib ignites the powder at several different places, and as the flame readily travels along the face of the plug, the powder is uniformly burned at an increasing rate, so producing an increasing uniform accelerating force against the powder plug, which in turn is transferred to the grippers of the powder plug.

By means of the device described, uniform results can always be obtained and with a minimum amount of labor. It does away with the old slow and tedious method, and also removes the necessity for haste and careless work on the part of the miner, due to the slowness of the old method. It not only saves time for the miner, but practically prevents blow-out shots or other serious disasters.

What I claim is:

1. A blasting device comprising a plug adapted for insertion into the powder or cartridge and provided with an igniting opening therethrough, pivoted expandable grippers associated with said plug and having their outer ends free to swing outwardly and adapted to grip the walls of the bore hole, and means for expanding said grippers.

2. A blasting device comprising a conical plug adapted for insertion into the powder or cartridge and provided with an igniting opening therethrough, pivoted expandable grippers associated with said plug and having their outer ends free to swing outwardly

and adapted to grip the walls of the bore-hole, and means for expanding said grippers.

3. A blasting device comprising a plug adapted for insertion into the cartridge and corrugated externally for securing the cartridge thereto and provided with an igniting opening therethrough, pivoted expansible grippers associated with said plug and having their outer ends free to swing outwardly, and means for expanding said grippers.

4. A blasting device comprising a plug adapted for inserting into the powder or cartridge and provided with an igniting opening therethrough, and with perforations communicating with said opening, pivoted expansible grippers associated with said plug and having their outer ends free to swing outwardly, and means for expanding said grippers.

5. A blasting device comprising a plug adapted for insertion into the powder or cartridge and provided with an igniting opening therethrough, pivoted expansible grippers associated with said plug and having their outer ends free to swing outwardly, and a wedge arranged to expand said grippers.

6. A blasting device comprising a plug provided with an igniting opening therethrough, pivoted expansible grippers associated with said plug and having their outer ends free to swing outwardly, a wedge for expanding said grippers and means for advancing said wedge.

7. A blasting device comprising a plug provided with an igniting opening therethrough, a bar connecting with said plug and provided with an opening communicating with said igniting opening, expansible grippers mounted on said bar, and a tube surrounding said bar and carrying means for expanding said grippers.

8. A blasting device comprising a plug provided with an igniting opening, expansible grippers associated with said plug, expanding means for said grippers, and a bar and tube, one connected to said plug and the other connected to said expanding means and

arranged for relative rotation to expand said grippers.

9. A blasting device comprising a plug provided with an igniting opening therethrough, a bar connected with said plug and provided with a hole communicating with said igniting opening, expansible grippers associated with said plug, a tube surrounding said bar, a conical wedge for expanding the grippers and having a threaded engagement with said bar, and means for producing relative rotation between said bar and tube to advance said conical wedge.

10. A blasting device comprising a plug provided with an igniting opening therethrough, expansible grippers associated with said plug, a bar connected to said plug and provided with a hole communicating with the igniting opening in the plug, a tube surrounding the bar and carrying means for expanding the grippers, and a sleeved plug around the outer end of said tube for steady ing the tube and bar.

11. A blasting device, comprising a conical plug adapted for insertion into the cartridge and provided with an igniting opening therethrough, a collar or disk at the base of the conical portion of the plug and of larger diameter than said base and forming a packing abutment for the cartridge, expansible grippers associated with said plug and means for expanding said grippers.

12. A blasting device, comprising a conical plug provided with an igniting opening therethrough and corrugated externally to provide means for the attachment of the cartridge thereto, a collar or disk on the outer end of said plug and of larger diameter than said corrugations and forming a packing abutment for the cartridge, expansible grippers associated with said plug, and means for expanding said grippers.

In testimony whereof, I have hereunto set my hand.

CHARLES P. McGREGOR.
